[57] ABSTRACT

The anti-bacterial agents of the invention present the following structural formula:

in which

R is a member selected from the group consisting of —H, alkanoyl of 2 to 6 carbon atoms, phenyl, and when n is zero, alkylidene of 3 to 6 carbon atoms and pyridylmethylene;

R² is a member selected from the group consisting of —H alkanoyloxy or 2 to 6 carbon atoms,

or when taken with the 3-carboxyl group

R³ is a member selected from the group consisting of —H, alkyl of 1 to 6 carbon atoms and aryl of 6 to 8 carbon atoms;

M is a member selected from the group consisting of —H, an alkali metal and —NH₄;

n is 0 or 1; and

the pharmaceutically acceptable hydrohalide addition salts thereof.

7 Claims, No Drawings

**7-[2-(N-AMINO
AMIDINOETHIO)ACETAMIDO]CEPHALOSPO-
RANIC ACIDS**

DESCRIPTION OF THE INVENTION

In accordance with this invention there is provided anti-bacterial agents of the formula:

in which

R is a member selected from the group consisting of —H, alkanoyl of 2 to 6 carbon atoms, phenyl, and when n is zero, alkylidene of 3 to 6 carbon atoms and pyridylmethylene;

with an appropriately substituted 7-(2-haloacetamido) cephalosporin derivative. The reaction occurs at ambient temperature in an inert polar organic solvent such as acetone or dimethylformamide to yield the hydrohalide salt of the 7-[2-(N-aminoamidinothio) acetamido] cephalosporanic acid derivative. The preparation of each of the semicarbazones and semicarbazides, as well

as the 7-(2-haloacetamido) cephalosporin derivatives is known in the chemical literature.

The preferred group of compounds, from the standpoint of availability of the reactants, ease of reaction and production economics, are those of the formula:

25

R² is a member selected from the group consisting of —H, alkanoyloxy of 2 to 6 carbon atoms,

or when taken with the 3-carboxy group

R³ is a member selected from the group consisting of —H, alkyl of 1 to 6 carbon atoms and aryl of 6 to 50 carbon atoms;

M is a member selected from the group consisting of —H, an alkali metal and —NH₄;

n is 0 or 1; and

the pharmaceutically acceptable hydrohalide addition salts thereof.

The term "alkyl", as it is used herein, is intended to embrace univalent aliphatic hydrocarbons containing from 1 to 6 carbon atoms such as, methyl, ethyl, propyl, i-propyl, butyl, i-butyl, amyl and hexyl. The term "aryl" is intended to embrace univalent aromatic hydrocarbons containing 6 to 8 carbon atoms such as, phenyl, tolyl, ethylphenyl and di-methylphenyl.

The compounds of this invention are prepared by reacting the appropriately substituted thiosemicarbazone or thiosemicarbazide of the formula:

35 in which

R is a member selected from the group consisting of —H, acetyl, phenyl and when n is 0, isopropylidene and 4-pyridylmethylene;

R² is a member selected from the group consisting of —H and acetoxy;

X is —Cl or —Br; and

n is 0 or 1.

The compounds of this invention have been found to be active anti-bacterial agents effective against gram-positive and gram-negative test organisms as well as penicillin resistant staphlococcus, by using the well known and scientifically accepted agar serial dilution testing technique. Thus, the compounds of this invention are useful in the fields of comparative pharmacology and in microbiology and for the treatment of bacterial infections amenable to treatment with penicillin and cephalosporin antibiotics.

The following examples illustrate the preparation of representative cephalosporin derivatives. The compounds produced in the following examples are generally recovered in the hydrohalide addition salt form, frequently with a small amount of solvent, the latter being readily removed by further vacuum stripping of the product. The free bases are readily formed by neutralization of the hydrohalide by conventional techniques. The activity of each exemplified product is presented for those specific bacterial strains against which the compound exemplified was active at or below 250 micrograms per milliliter. The representative nature of the bacterial strains employed to demonstrate anti-bacterial activity are indicative of the broader applicability of the compounds of this invention in the control of bacterial infestations other than

those specifically referred to in each of the following examples. The bacteria are named followed by the specific strain and the concentration in micrograms per milliliter at which 100 percent inhibition occurred. The abbreviations for each bacterium are:

BA SU	<i>Bacillus subtilis</i>
BO BR	<i>Bordetella bronchiseptica</i>
ES CO	<i>Escherichia coli</i>
ES IN	<i>Escherichia intermedia</i>
HE SP	<i>Herellea species</i>
KL PN	<i>Klebsiella pneumoniae</i>
NE CA	<i>Neisseria catarrhalis</i>
PR VU	<i>Proteus vulgaris</i>
SA PA	<i>Salmonella paratyphi</i>
ST AU	<i>Staphylococcus aureus</i>

EXAMPLE I

7-[2-(N-Acetamidoamidinothio)acetamido]cephalosporanic acid hydrobromide.

An acetone solution of acetylthiosemicarbazide (0.27 gram, 2 millimole) and 7-(2-bromoacetamido)cephalosporanic acid (0.78 gram, 2 millimole) was stirred at room temperature overnight. After a small amount of insoluble material was filtered, the solvent was removed. The solid residue (0.7 gram) was treated with diethyl and ether and collected.

Elemental Analysis for $C_{15}H_{19}N_5O_7S_2 \cdot HBr \cdot (C_2H_5)_2O$: Calc'd: C, 37.99; H, 5.04; N, 11.66. Found: C, 38.31; H, 4.76; N, 11.37.

EXAMPLE V

2-(4-Pyridylmethylenehydrazinoimidocarbonylthio)acetamido cephalosporanic acid hydrobromide.

The thiosemicarbazone of 4-pyridylcarboxaldehyde (0.36 gram, 2 millimole) and 7-(bromoacetamido)cephalosporanic acid (0.78 gram, 2 millimole) were dissolved in dimethylformamide, and the solution was stirred at room temperature for 2 hours. After the solvent was removed in vacuo below 30°C. the residue was treated with acetone. The product which appeared as a polymorphous solid, weighed 0.55 gram. On concentration of this filtrate an additional 0.5 gram of product was recovered.

Elemental Analysis for $C_{19}H_{20}N_6O_6S_2 \cdot HBr \cdot 3H_2O$: Calc'd: C, 37.66; H, 5.03; N, 13.97. Found: C, 37.66; H, 4.02; N, 14.01.

2. A compound of claim 1 of the formula:

5

What is claimed is:

1. A compound of the formula:

in which

R is a member selected from the group consisting of
—H, alkanoyl of 2 to 6 carbon atoms or phenyl,
when n is 1, and alkylidene of 3 to 6 carbon atoms
or pyridylmethylene, when n is zero;

R² is a member selected from the group consisting of
—H, alkanoyloxy of 2 to 6 carbon atoms and, when
taken with the 3-carboxy group,

M is a member selected from the group consisting of
—H, an alkali metal and —NH₄;

n is 0 or 1; and

the pharmaceutically acceptable hydrohalide addition
salts thereof.

10

in which

15 R is a member selected from the group consisting of
—H, acetyl or phenyl, when n is 1, and isopropylidene or 4-pyridylmethylene, when n is zero;

R² is a member selected from the group consisting of
—H and acetoxy;

20 X is —Cl or —Br; and
n is 0 or 1.

3. The compound of claim 1 which is 7-[2-(N-acetamidoamidinothio)acetamido]cephalosporanic acid and the hydrohalide addition salts thereof.

4. The compound of claim 1 which is 7-[2-(N-anilinoamidinothio)acetamido]cephalosporanic acid and the hydrohalide addition salts thereof.

5. The compound of claim 1 which is 7-[2-(N-isopropylideneaminoamidinothio)acetamido]cephalosporanic acid and the hydrohalide addition salts thereof.

6. The compound of claim 1 which is 7-[2-(N-aminoamidinothio)acetamido]cephalosporanic acid and the hydrohalide addition salts thereof.

35 7. The compound of claim 1 which is 2-(4-pyridylmethylenehydrazinoimidocarbonylthio)acetamido cephalosporanic acid and the hydrohalide addition salts thereof.
